UNITED STATES PATENT OFFICE.

BERNARD A. GEURINK, OF EAST CLEVELAND, OHIO, ASSIGNEE TO THE TRENKAMP STOVE & MANUFACTURING COMPANY, OF CLEVELAND, OHIO, A CORPORATION OF OHIO.

GAS-BURNER.

939,242.

Specification of Letters Patent. Patented Nov. 9, 1909.

Application filed June 12, 1909. Serial No. 501,758.

To all whom it may concern:

Be it known that I, BERNARD A. GEURINK, a citizen of the United States, and a resident of East Cleveland, county of Cuyahoga, and State of Ohio, have invented a new and useful Improvement in Gas-Burners, of which the following is a specification, the principle of the invention being herein explained and the best mode in which I have contemplated applying that principle, so as to distinguish it from other inventions.

The object of the invention is the provision of a gas burner wherein a more thorough combustion and correspondingly economical use of the fuel is obtained than in the prevailing constructions, by so disposing the several parts of the burner that the air necessary to complete combustion may have free access to all such parts.

To the accomplishment of this object, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:—Figure 1 is a plan view of a burner embodying my improved construction; Fig. 2 is a central vertical section of the same on the line 2—2 Fig. 1; and Fig. 3 is a plan view, on a smaller scale of a modified construction of burner.

The mixing chamber A of my improved burner need not differ from that ordinarily employed in similar connections; the gas is admitted through the central opening α from a supply pipe (not shown) and there intermixed with a proper amount of air, such air supply being controlled by adjustment of the apertured plate α' that closes the outer end of the combustion chamber.

It is to the burner proper that particular attention is desired. This will be seen to comprise an outward annular chamber B directly connected with such mixing chamber A, from which annular chamber arms b extend radially inward toward the center of the burner but do not meet, so that such center is left unobstructed. The number of arms b may vary, but will preferably be four, as shown, and should the diameter of the burner be such as to leave too much

space between the adjacent radiating arms, other shorter arms b' may be provided between the aforesaid arms, as shown in Fig. 3. Such shorter arms likewise do not meet with the longer arms, but an unobstructed passage for air is left around each arm, whether short or long. The outer annular chamber, together with the arms are provided with apertures b^2 for the escape of the gas therefrom, which apertures may be in the form of jets or otherwise, as found best suited to the particular fuel employed.

From the foregoing construction of my improved burner, it will be obvious that air is supplied freely to the gas issuing from both the annular chamber and the several arms of the burner, and that particularly the gas discharged from the inner ends of the radiating members, is afforded an ample supply to insure a clear, clean flame. This is a marked distinction from the more familiar construction of burner, wherein the arms radiate outwardly from a central chamber. In burners thus constructed, while the gas may burn clear at the outer ends of the arms, there is apt to be an insufficient supply of air for the complete combustion of the gas discharged from the center, and even where the gas is permitted to escape from the arms only, the center being left blank, it is obvious that there exists a dead space in the center of the burner that more or less affects the burning of the gas issuing from the circumjacent jets.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention:—

1. A gas burner comprising an outer annular chamber, and inwardly directed radial arms communicating therewith, said chamber and arms being provided with apertures for the escape of the gas therefrom, and the space between the ends of said arms and on either side thereof being left open, substantially as and for the purpose described.

2. A gas burner comprising an outer annular chamber, and radial arms extending inwardly therefrom toward the center of the burner, but out of contact with each other,

whereby such center and the space on either side of said arms is left unobstructed, said chamber and arms being provided with apertures for the escape of the gas therefrom, 5 substantially as and for the purpose described.

3. A gas burner comprising an outer annular chamber, radial arms extending inwardly toward the center of the burner but 10 not meeting, whereby such center is left un-

obstructed, and other shorter arms located between aforesaid arms, said chamber and arms being provided with apertures for the escape of the gas therefrom, and the space between said arms being left open.

Signed by me this 8th day of June, 1909. 15

BERNARD A. GEURINK.
